UNITED STATES PATENT OFFICE.

ORVILLE H. McMURRAY, OF SPRINGFIELD, MISSOURI.

WRENCH.

SPECIFICATION forming part of Letters Patent No. 659,090, dated October 2, 1900.

Application filed June 1, 1900. Serial No. 18,740. (No model.)

To all whom it may concern:

Be it known that I, ORVILLE H. McMURRAY, a citizen of the United States, residing at Springfield, in the county of Greene and State 5 of Missouri, have invented new and useful Improvements in Wrenches, of which the following is a specification.

This invention relates to new and useful improvements in wrenches; and its primary 10 object is to provide a wrench which is simple, durable, and economical and capable of being expeditiously and conveniently adjusted to any size nut and its jaws firmly locked in engagement with said nut when the proper adjustment has been made.

A further object is to provide a locking means which may be readily detached from the jaws.

To these ends the invention consists in the 20 novel construction and combination of parts hereinafter more fully described and claimed and illustrated in the accompanying drawings, showing the preferred form of my invention, and in which—

25 Figure 1 is a perspective view thereof. Fig. 2 is a longitudinal section, and Fig. 3 is a detail view of the locking-lever detached.

Referring to said figures by numerals of reference, 1 is a shank having a fixed jaw 2 formed 30 therewith and provided with teeth 3 upon one of its surfaces. A handle 4, of suitable form and construction, is secured to the end of this shank in any desired manner.

Slidably mounted upon the shank 1 is a jaw 35 5, which is provided with a groove 6 in the rear face thereof adjacent to the teeth 3, and the walls of said recess are slotted, as at 7, at an incline, as shown. Fitted within these slots 7 are trunnions 8, extending from opposite sides of the end of a lever 9, which projects from the groove 6 and is preferably curved, as shown. A spring 10 is secured within the groove 6, and the free end thereof bears upon the outer surface of the lever 9, holding the same normally in contact with the adjacent face of the shank 1. This spring 45 is preferably formed of wire coiled at its center, as at 11, said coil being located wholly within the groove 6.

50 Teeth 12 project from the inner face of the

lever 9 and are adapted to engage with the corresponding teeth upon the face of the shank.

It will be seen that when the sliding jaw 5 is moved toward the fixed jaw 2 the lever 9 and its teeth 12 will slip over the teeth of the shank. When the motion of the jaw is reversed, the teeth of said lever will be pressed into engagement with the shank by means of the spring 10. It will be seen that the lever 60 9 is reduced in thickness at a point near the trunnions 8, as at 13. This reduced portion will register with the slots 7 when the lever is raised out of engagement with the teeth of the shank 1, and can then be slid laterally 65 from the jaw, as will be obvious.

In the foregoing description I have shown the preferred form of my invention; but I do not limit myself thereto, as I am aware that modifications may be made therein without departing from the spirit or sacrificing the advantages thereof, and I therefore reserve the right to make such changes and alterations as fairly fall within the scope of my invention.

Having thus fully described my invention, what I claim as new, and desire to secure by Letters Patent, is—

1. The combination with a shank and fixed jaw, of a sliding jaw upon the shank having 80 a groove in the rear face thereof and slots in the walls of said groove, a lever journaled within the slots and adapted to engage the shank, said lever adapted to register with, and slide within the slots when disengaged 85 from the shank.

2. The combination with a shank and a fixed jaw, of a sliding jaw upon the shank having a groove in the rear face thereof and slots within the walls of said groove, a lever within 90 the groove and having trunnions bearing in said slots, and a spring for normally holding said lever in engagement with the shank, said lever adapted to register with, and be moved laterally within, the slots when disengaged 95 from the shank.

3. The combination with a toothed shank having a fixed jaw, of a jaw slidably mounted thereon provided with a groove within its rear face and slots in the walls of said groove, a 100

lever within the groove, trunnions thereto bearing within the slots, teeth upon the lever normally engaging the teeth of the shank, and a spring within the groove and bearing upon the lever, said lever adapted to register with, and be moved laterally within, the slots of the jaw when disengaged from the shank.

In testimony whereof I affix my signature in presence of two witnesses.

ORVILLE H. McMURRAY.
